US0D1049495S

(12) **United States Design Patent** (10) Patent No.: **US D1,049,495 S**
(45) Date of Patent: ** Oct. 29, 2024

(54) **NAIL CLIPPER**

(71) Applicant: **Huan Zhang**, Nanjing (CN)

(72) Inventor: **Huan Zhang**, Nanjing (CN)

(**) Term: **15 Years**

(21) Appl. No.: **35/519,472**

(22) Filed: **Nov. 14, 2023**

(80) **Hague Agreement Data**

Int. Filing Date: **Nov. 14, 2023**

Int. Reg. No.: **DM/233821**

Int. Reg. Date: **Nov. 14, 2023**

Int. Reg. Pub. Date: **Dec. 22, 2023**

(51) **LOC (14) Cl.** 28-03

(52) **U.S. Cl.**

USPC **D28/60**

(58) **Field of Classification Search**

USPC D28/60

CPC . A45D 29/02; A45D 29/023; A45D 2029/026

See application file for complete search history.
